UNITED STATES PATENT OFFICE

118,493

DESIGN FOR A SHOE OR SIMILAR ARTICLE

Israel Berman, New York, N. Y.

Application December 7, 1939, Serial No. 88,742

Term of patent 3½ years

To all whom it may concern:

Be it known that I, Israel Berman, a citizen of the United States of America, residing in the city of New York, county of New York, and State of New York, have invented a new, original, and ornamental Design for a Shoe or Similar Article, of which the following is a specification, reference being had to the accompanying drawing, forming part thereof.

Fig. 1 is a plan view of a shoe or similar article showing my new design.

Fig. 2 is a side elevational view thereof.

I claim:

The ornamental design for a shoe or similar article, substantially as shown.

ISRAEL BERMAN.
